(57) CLAIM

The ornamental design for a take-off trailer body, as shown and described.

DESCRIPTION

FIG. 1 is a rear elevation view of a take-off trailer body showing my new design;

FIG. 2 is a front elevation view thereof;

FIG. 3 is a left side elevation view thereof;

FIG. 4 is a right side elevation view thereof; and,

FIG. 5 is a top plan view thereof.

The broken lines shown in the figures are for illustrative purpose only and form no part of the claimed design.
